UNITED STATES PATENT OFFICE.

ERNEST J. SIEBER, OF ROSS TOWNSHIP, ALLEGHENY COUNTY, PENNSYLVANIA,
ASSIGNOR TO STANDARD SANITARY MANUFACTURING COMPANY, OF PITTSBURGH, PENNSYLVANIA, A CORPORATION OF NEW JERSEY.

MIXING-VALVE.

1,203,798.

Specification of Letters Patent.

Patented Nov. 7, 1916.

Application filed November 30, 1914. Serial No. 374,739.

To all whom it may concern:

Be it known that I, ERNEST J. SIEBER, residing at Ross township, in the county of Allegheny and State of Pennsylvania, a citizen of the United States, have invented or discovered certain new and useful Improvements in Mixing-Valves, of which improvements the following is a specification.

My invention relates to mixing valves, and, while not limited to any specific purpose, is particularly adapted to be used for mixing hot and cold water and for regulating its temperature for baths and like purposes.

15 The object of my invention is to provide a mixing valve having increased efficiency and of improved construction and operation.

20 A further object is to provide such a valve comprising a small number of movable parts, which, neither because of inherent construction nor wear of service, will rattle or hammer when the valve is open.

25 One embodiment of my invention is illustrated in the accompanying sheets of drawings which form part of my specification.

Figure 1 is a face view of the valve and pipes connected to it; Fig. 2 a combined elevation and sectional view, the plane of view being taken on the broken line II-II, Fig. 1; Fig. 3 a sectional view taken on the line III-III, Fig. 2; Fig. 4 a face or plan view of the integral valve casing with all the operating and attached parts removed; 35 and Fig. 5 a sectional view taken on the line V-V, Fig. 4.

In the several figures like numerals are used to designate like parts.

The essential elements of the valve construction consist of a casing affording inlet chambers and an outlet and mixing chamber communicating by ports with the inlet chambers, valve members for opening and closing the ports and for varying with relation to each other, the quantities of fluid flowing through the ports, and means for operating the valve members. The valve casing 1, in the present embodiment of my invention, is cylindrical and is provided interiorly with walls 2 and 2^a which divide the casing into inlet chambers 3 and 3^a and an outlet and mixing chamber 4, the inlet chambers being on opposite sides of the center of the casing. The inlet chambers

communicate with the outlet chamber by 55 means of ports 5 and 5^a, and the several chambers 3, 3^a and 4 are provided with pipe connection openings 6, 6^a and 7, respectively. The casing is further provided with guideways 8 and 8^a, above and in line with the ports 5 and 5^a, and preferably cylindrical in form adjacent to the ports but incomplete cylinders near the open side of the casing. Between the truly cylindrical portions of the guideways, and centrally disposed within the casing, there is a bearing 9 to support the valve operating member, as will be fully explained hereinafter. The casing as thus described is an integral casting of any suitable material. 70

As stated above, the valve members for the ports 5 and 5^a are effective in the first place to close the ports when the valve is in closed position, and in the second place to vary, with relation to each other, the 75 quantities of fluid flowing through the ports when the valve is opened. For these purposes they are preferably two-part members consisting of stems 11 and 11^a mounted in the guideways 8 and 8^a, respectively, the 80 lower ends of such stems being adapted to seat upon the rims of the ports, and graduated plugs 10 and 10^a secured to the stems and projecting through the ports. The plugs may be of any suitable construction 85 to the end that, as they are simultaneously moved through their ports, the quantity of fluid passing through one port will be gradually increased, while that passing through the other will be gradually decreased. As 90 shown herein, the plugs are oppositely tapered, and when the mixing valve is used for hot and cold water, the plug 10 will be for the cold water and 10^a for the hot water port. Preferably the plugs and stems are 95 rigidly connected to each other as by the screw thread attachment shown in Fig. 2. Also, in order to effectively close the ports when no fluid is required, the inner valve-forming ends of the stems 11 and 11^a are 100 provided with packing disks 12 and 12^a.

The valve operating member consists of a spindle 13 and a laterally projecting disk 14, which is preferably formed integrally with the spindle, and is provided with 105 screw-threads adapted to engage corresponding threads formed on concave surfaces of the valve stems 11 and 11^a. As

shown in Fig. 3 the disk 14 is provided with four threads the pitch of which is such that the valve members may, by giving the spindle less than a complete turn, be moved 5 through their permissible range of travel. The operating member is rotatable, but is held against longitudinal movement on the one side by the bearing support 9 and on the other side by a cover 15, secured to 10 the casing as by screws 16. To give the structure a neat appearance, a suitable canopy or second cover 17 may extend over the front of the casing and be clamped between nuts 18 and 19, as clearly shown in 15 Fig. 2. In order to properly adjust the extent of the movement of the valve members, a suitable set or stop screw 23 may be inserted in the end of one of the valve members, and the extent of its projection 20 above the top of the spindle may be regulated by first removing a screw 24 from the cover 15 and then inserting a suitable screw driver through the opening in the cover, as will be understood from Fig. 2. When in- 25 stalled the inlet chambers 3 and 3^a are placed in communication with sources of fluid supply by means of inlet pipes 20 and 20^a, and a third pipe 21 leads from outlet chamber 4, as seen in Fig. 1.

30 In operation, assuming the parts to be in the positions indicated in Fig. 2, by turning a handle 22 secured to the spindle 13, the valve stems 11 and 11^a will be caused to slide along their guideways 8 and 8^a. Thus 35 the plugs 10 and 10^a will move through their ports 6 and 6^a, respectively, thereby permitting the fluids to enter the outlet chamber and be mixed therein in the well-known manner.

40 Because of the rigid construction of the valve members, including the plugs and stems, and the direct threaded engagement of the valve guides with the disk 14, it will be seen that there can be no rattling or ham- 45 mering of the valve members. Furthermore the relatively large bearing or contact surfaces of the movable parts, made possible by my improved construction, materially contribute toward the durability of the construction, and its efficiency and ease of 50 operation. Finally, the valve members being separate and disconnected from each other, the wear upon one valve member, or upon its threaded engagement with the operating stem, will have no prejudicial effect 55 upon the seating of the other valve member or upon its intended control of fluid through its co-operating port.

I claim as my invention:

60 1. In a mixing valve, the combination of a casing comprising a pair of oppositely disposed inlet chambers, a mixing and outlet

chamber communicating by ports with the inlet chambers, and guideways for valve members; a pair of valve members uncon- 65 nected to each other and comprising oppo- sitely graduated plugs adapted to control flow through said ports, and stems secured to said plugs and movable in said guideways, the adjacently disposed faces of said stems 70 being provided with screw threads; and a rotatably mounted operating spindle having a laterally-projecting exteriorly-threaded disk engaging said threaded faces of the stems. 75

2. In a mixing valve, the combination of a casing comprising a pair of oppositely disposed inlet chambers, a mixing and outlet chamber communicating by valve controlled ports with the inlet chambers, and guide- 80 ways for valve members; a pair of valve members unconnected to each other and comprising oppositely graduated plugs adapted to control flow to said ports, and stems secured to said plugs and movable in 85 said guideways, the adjacently disposed faces of said stems being provided with screw threads the general planes of which substantially coincide with the longitudinal axes of said plugs; and a rotatably mounted 90 operating spindle having a laterally-projecting exteriorly-threaded disk engaging said threaded faces of the stems.

3. In a mixing valve, the combination of an integrally formed cylindrical casing 95 member comprising inlet chambers, a mixing and outlet chamber communicating by ports with the inlet chambers, oppositely disposed guideways for valve stems and a centrally disposed bearing support for an 100 operating spindle; valve members at oppo- site sides of the center of the casing and comprising oppositely tapered plugs projecting through said ports, and stems slidably mounted in said guideways and adapted to close said ports, said plugs being rigidly connected to the stems, and the valve guides having concave interiorly facing surfaces provided with screw threads; an operating spindle having its inner end rotatably mounted in said bearing support and having as an integral part thereof a laterally pro- 105 jecting disk provided with screw threads engag- ing those of said valve stems and a cover secured to said casing, said operating member being held against longitudinal movement by said bearing support and cover. 110

In testimony whereof I have hereunto set my hand.

ERNEST J. SIEBER.
